UNITED STATES PATENT OFFICE.

JOSEPH A. HAGGERTY, OF PHILADELPHIA, PENNSYLVANIA.

HAIR CURLER AND WAVER.

1,322,899.

Specification of Letters Patent. Patented Nov. 25, 1919.

Application filed June 25, 1919. Serial No. 306,516.

To all whom it may concern:

Be it known that I, JOSEPH A. HAGGERTY, a citizen of the United States, residing at Philadelphia, in the county of Philadelphia and State of Pennsylvania, have invented 5 certain new and useful Improvements in Hair Curlers and Wavers, of which the following is a specification.

One object of my invention is to provide 10 an improved device which can be conveniently used for curling or waving the hair.

Another object is to so construct my improved device that it can be easily locked and will not accidentally become unfastened. 15

A further object is to so design my improved hair-curler and waver that it can be manufactured and sold at a comparatively low cost. 20

These objects, and other advantageous ends which will be described hereinafter, I attain in the following manner, reference being had to the accompanying drawing in which— 25

Figure 1 is a top plan view of my invention in a closed or fastened position,

Fig. 2 is a side elevation of Fig. 1, showing in dot-and-dash lines how the hair can be curled around one of the sections thereof 30 and serve to expand or bow the sections,

Fig. 3 is a top plan view showing the device part way open and also illustrating how the hair can be wound around one of the sections prior to fastening the sections 35 together, and

Fig. 4 is a fragmentary elevation showing how the sections appear when locked together, and drawn on a larger scale than illustrated in Figs. 1 to 3 inclusive.

Referring to the drawing, my improved 40 device consists of two sections 5 and 6 which are preferably made of resilient sheet metal and are pivoted together by an eyelet hinge 7. The section 6 has a handle 8 on its outer 45 end, said handle including a contracted or narrow neck portion 9 which is produced by inwardly curving the section 6 at 10. The section 5 has a notch 11, said notch including a narrow entrance or mouth 12 so

50 as to provide a shoulder 13 directly adjacent the inner portion of the mouth. The portion 14 of the section 5, including the notch 11, is bent at an angle, as clearly shown in Figs. 2 and 4, and the neck portion 9 of the 55 section 6 is so arranged that when the sections 5 and 6 are moved so as to overlap each

other, the neck 9 will enter the notch 11 through the entrance or mouth 12 and will occupy a position, such as clearly shown in Fig. 1. 60

By bowing the sections as clearly shown in Fig. 2, which action occurs when the sections are closed with the hair curled thereon, the neck 9 will be held between the shoulder 13 and the inner end 15 of the notch 11 so 65 that the sections will not accidentally become unfastened. In other words, by slightly compressing the free ends of the sections 5 and 6, after the hair has been wound thereon, the neck 9 can be slipped 70 into the notch 11 through the entrance 12 and when manual pressure is released, the hair will expand and thereby cause the free end portions to extend at abrupt angles which are oppositely disposed to each other, 75 and said action will cause the neck 9 to press against the edge 16 within the notch and being thus positioned the neck cannot move out of the entrance 12 until the sections are manually pressed toward each 80 other.

While I have described the hair, such for example as illustrated at 17, as being wrapped around the member 6, it will be understood that if desired the hair can be 85 wrapped around the member 5; this being at the option of the user.

The section 5 is preferably provided with an angular bend 18, as clearly shown in Fig. 2, adjacent the pivot 7. This provides 90 a normal separation of the sections, sufficient to permit them to be easily manipulated and also to provide a space so that the parts will not have to be bowed to the full extent of the thickness of the hair. 95

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims. 100

Having thus described my invention, what 105 I claim as new and desire to secure by Letters Patent is:—

1. A hair-curler and waver including two sections movably secured together, one of said sections having a notch including an 110 entrance opening thereto located in a side edge thereof and of less width than the in-

- terior of the notch and providing a shoulder between the entrance and the inner end of the notch, said other section having a portion movable into the notch through said 5 entrance and adapted to engage between said shoulder and said end of the notch whereby the sections are prevented from accidentally moving apart; substantially as described.
- 10 2. A hair-curler and waver including two sections pivoted together, one of said sections having a notch including an entrance opening thereto located in a side edge thereof and of less width than the interior of the 15 notch whereby a shoulder is provided, said other section having a portion adapted to enter said notch through the entrance opening and position itself between said shoulder and the inner end of the notch; substantially as described.
- 20 3. A hair-curler and waver including two sections pivoted together, one of said sections having a notch including an entrance opening thereto located in a side edge thereof and of less width than the interior of the 25 notch whereby a shoulder is provided, said other section having a portion adapted to enter said notch through the entrance opening and position itself between said shoulder and
- the inner end of the notch, said second section having a handle projecting from the portion which enters said notch; substantially as described. 30
4. A hair-curler and waver including two sections pivoted together, one of said sections 35 having a notch including an entrance opening thereto located in a side edge thereof and of less width than the interior of the notch whereby a shoulder is provided, said other section having a portion adapted to 40 enter said notch through the entrance opening and position itself between said shoulder and the inner end of the notch, said portion which includes said notch being bent at an angle toward the plane of movement of 45 the other section whereby said portion of the second mentioned section which enters the notch will extend at an angle to the portion including the notch; substantially as described. 50

In testimony whereof I have signed my name to this specification in the presence of two subscribing witnesses.

JOSEPH A. HAGGERTY.
